(57) **CLAIM**

The ornamental design for a fishing lure, as shown and described.

DESCRIPTION

FIG. 1 is a perspective view of a fishing lure, showing a first embodiment of my new design;

FIG. 2 is a front elevational view of FIG. 1, the rear elevational view being a mirror image thereof;

FIG. 3 is a left-side elevational view of FIG. 1, the right-side elevational view, top plan view, and bottom plan view all being identical thereto;

FIG. 4 is a perspective view of a second embodiment thereof;

FIG. 5 is a front elevational view of FIG. 4, the rear elevational view being a mirror image thereof;

FIG. 6 is a left-side elevational view of FIG. 4, the right-side elevational view, top plan view, and bottom plan view all being identical thereto;

FIG. 7 is a perspective view of a third embodiment thereof;

FIG. 8 is a front elevational view of FIG. 7, the rear elevational view being a mirror image thereof;

FIG. 9 is a left-side elevational view of FIG. 7, the right-side elevational view, top plan view, and bottom plan view all being identical thereto;

FIG. 10 is a perspective view of a fourth embodiment thereof;

FIG. 11 is a front elevational view of FIG. 10, the rear elevational view being a mirror image thereof; and,

FIG. 12 is a left-side elevational view of FIG. 10, the right-side elevational view, top plan view, and bottom plan view all being identical thereto.

The broken lines in FIGS. 1, 4, 7, and 10 showing hooks and fishing lure components depict environmental matter and form no part of the claimed design.
